UNITED STATES PATENT OFFICE.

WILLIAM TAYLOR, OF EDINBURGH, SCOTLAND.

APPARATUS FOR HEATING AIR FOR THERAPEUTIC OR OTHER PURPOSES.

SPECIFICATION forming part of Letters Patent No. 608,928, dated August 9, 1898.

Application filed December 21, 1897. Serial No. 662,835. (No model.)

To all whom it may concern:

Be it known that I, WILLIAM TAYLOR, M. D., F. R. C. P. E., a subject of the Queen of Great Britain and Ireland, and a resident of 5 Edinburgh, Scotland, have invented certain Improvements in Apparatus for Heating Air for Therapeutic or other Purposes, of which the following is a specification.

My said invention has for its object to combine or arrange portable apparatus for conveniently and expeditiously producing currents of air or gas of any required temperature within moderate limits for therapeutic and other purposes, and as an example I may state 15 that when neuralgic or other pain is due to a cold draft or chill relief is obtainable by directing a suitably-heated current of air upon the affected part.

The apparatus comprises means for imparting motion to the air or gas, combined with means for heating it; and in order that my said invention and the manner of performing the same may be properly understood I hereunto append a sheet of explanatory drawings, 25 to be hereinafter referred to in particularly describing my improvements.

Figure 1 on the accompanying sheet of drawings is a plan, Fig. 2 an elevation, and Fig. 3 a vertical section, of my improved apparatus. In these drawings the same reference-letters are used to mark the same or like 30 parts wherever they are repeated.

As shown in the drawings, there is a piece of spring-actuated clockwork inclosed in a casing A, and such as is employed for supplying air to some kinds of lamps, the clock-work being wound up by means of a thumb-key B and being arranged to drive a fan C through a star-wheel D and worm E. The 35 fan C and its motor are inclosed in an outer casing F, the bottom of which serves as a stand for the apparatus. The upper end of the casing F is fitted with a lining-ring G, of rubber or other suitable material, adapted to receive the lower open end of a tube H, preferably of glass, within which a smaller glass tube J is held. The fan C draws air (or it might be gas) from the interior of the casing F, the air entering the casing through 40 holes K in the bottom part, and the fan propels the air through the inner tube J and also 45 between it and the outer tube H, which latter

terminates in a nozzle L, suitable for directing the current as required. When an electric current is available, the fan may be driven 55 by a small electric motor.

Electricity is employed to heat the air or gas in its passage through the tubes H J, a coil of fine wire, preferably platinum, and shown by dotted lines M, being wound on the inner tube 60 J, and the ends of the wire M being attached to screw-terminals N, fixed in the outer tube H. External conducting-wires P are attached to these terminals N; and an electric current is sent through these wires P of such 65 a voltage as serves to heat the platinum wire M. The current of air or gas in passing through the tubes H J, as hereinbefore described, becomes heated and emerges from the directing-nozzle L. The air may possibly be 70 electrified in passing over the wire M.

A slight hollow Z is formed in the lower side of the tube H near the nozzle L, in which hollow Z a small quantity of volatile liquid may be placed, the vapor from such liquid mixing 75 with the heated air or gas.

The temperature to which the heated current of air or gas is raised may be modified to suit different cases by means of adjustable resistances, (not shown,) through which the 80 electric current is passed.

The outer glass tube H may be made with the directing-nozzle part L of considerable length in comparison with that part of the modification hereinbefore described, and the 85 inner glass tube J, with the heating platinum wire M, may be held in that part L. In Fig. 3 the nozzle L is shown as formed on the unbent end of the tube H.

For the purpose of being conveniently held 90 in the hand in a horizontal or other position the casing F may be made without a bottom stand, holes K for admitting air to the interior of the casing being formed in a ring, which may turn with the thumb-key B. 95

What I claim as my invention is—

The herein-described portable apparatus for producing a heated current of air or gas for therapeutic or other purposes, comprising a casing, a directing-tube mounted upon and 100 carried by the said casing, a tube of non-conducting material concentrically within said directing-tube, an exposed resistance-coil mounted upon the said concentric tube and

forming part of an electric circuit, and means within the casing for forcing a continuous current of air or gas through the directing and concentric tubes, whereby air or gas passing through the concentric tube and between the outer walls of said tube and the inner walls of the directing-tube is heated thereby, substantially as specified.

In testimony whereof I have signed my name to this specification in the presence of 10 two subscribing witnesses.

WILLIAM TAYLOR.
